ADALBERT ZOLLINGER, OF LEIPZIG-EUTRITSCH, GERMANY, ASSIGNOR TO FIRM OF POPPER & CO., OF LEIPZIG, GERMANY.

MUSIC-RECORDING AND AUTOMATIC PLAYING DEVICE FOR ORGANS AND LIKE INSTRUMENTS.

1,004,839.

Specification of Letters Patent.

Patented Oct. 3, 1911.

Application filed July 22, 1910. Serial No. 573,188.

To all whom it may concern:

Be it known that I, ADALBERT ZOLLINGER, a subject of the Grand Duke of Baden, residing at Leipzig-Eutritsch, in Germany, have invented a certain new and useful Improvement in Music-Recording and Automatic Playing Devices for Organs and Like Instruments, of which the following is a specification.

10 The object of the present invention is to provide means whereby music manually played on an organ or like instrument with the aid of all the stops, couplings and other auxiliary devices with which such instrument is provided is automatically recorded on a music sheet and can then be automatically played on the same instrument with the aid of said sheet.

20 The invention is illustrated in the annexed drawings as applied to an organ of known type wherein the motor pneumatics controlling the valves of the organ pipe are arranged in so-called register-chambers, to which compressed air is admitted while the 25 pneumatics are contracted by suction.

25 In the drawings Figure 1 is a diagrammatic view of the playing and recording mechanism partly in section and Fig. 2 is a sectional plan view of part of the wind-chest 30 with pipes thereon, the top board and pipes having been removed.

35 The organ pipes 1 are arranged in rows upon the wind chest 1^a, which is divided by partitions 2 into register chambers R¹, R², etc. Each row of pipes parallel with the plane of the drawing has an air channel S, and each pipe has a valve 3 which is opened and closed by means of a motor pneumatic or bellows 4, the valves 3 being opened by 40 collapse of the pneumatics when the air is sucked from the latter through ports 4^a into the channel S.

45 The channels S are normally closed against the exhaustion of air therefrom, by means of valves 9^c, but such valves may be opened to connect the channels with a suction chamber 9^d, by the admission of atmospheric air into a chamber 9^a beneath a diaphragm or membrane 9^b with which the 50 valves 9^c are individually connected. The valves 8^e are in turn connected to membranes 8^b which constitute movable walls of cham-

bers 8^a, and the latter said chambers connect with the upper ends of a plurality of pipes or conduits 7. Admission of air to a chamber 8^a from a pipe 7 causes the valve 8^e to open to admit atmospheric air to a chamber 9^a, the effect of which is to lift the membrane 9^b and to open the valve 9^c so as to open the suction box 9^d to the selected channel S.

55 At their lower ends the conduits or pipes 7 are connected with ducts 7^b, which can be opened to the atmosphere by means of valves 5 operated by the manual keys 5^a, and they 60 are also provided with branches 7^a which connect with openings in a tracker board 6. A perforated record sheet as shown at 65 25, may be caused to travel over the tracker board, in a manner well known in connection with instruments of this character and thereby to admit air at the proper moment to the required pipes 7.

70 Each register chamber R has an opening 9 normally closed by a valve 9. This valve 75 9 is actuated by means of a pneumatic 10 and is opened when the pneumatic 10 is evacuated and collapses. The valves 9 and the pneumatics 10 are located in chambers 80 10^a containing compressed air. For sounding one of the organ pipes, not only is the respective valve 3 opened and also the valve 9 of the respective register chamber R.

75 The valves 9 and pneumatics 10 are actuated by the following arrangement. A 85 register-push 11 is connected by a rod 12, bell-crank 12^a and rod 12^b to a valve 13, which, when open admits atmospheric air to a chamber 14^a below a membrane 14, which divides said chamber 14^a from a chamber 90 14^b containing attenuated air. The membrane 14 lifts a valve 15 normally depressed by compressed air in a wind-chest 15^b. Lifted by the membrane 14 through the valve chamber 15^a the valve 15 closes a 95 port 15^c and cuts off the flow of compressed air to a pipe 16, which leads to one of the pneumatics 10. The latter thereupon collapses, discharging its air through pipe 16 and port 14^c into the suction chamber 14^a. 100 Each of the chambers 14^a is likewise provided with a pipe or conduit 26 which leads to the tracker board 6, in the same manner as above described in connection with the

pipes or conduits 7, but it must be remembered that while there is a pipe or conduit 7 for each note to be played, the number of the pipes or conduits 26 is limited by the 5 number of register chambers R¹, R² etc. employed.

For manual playing the required register-push or "stop" 11 is manipulated, one or more being pulled out as may be desired, 10 and thereafter the manual keys 5^a are depressed in the usual manner. The operation of the proper pneumatic or pneumatics 10 to open the required valve or valves 9 so as to select the series or row or rows of 15 pipes 1 to be played is effected by the manipulation of the stop or stops 11 as aforesaid, while thereafter the depression of a key 5^a selects the particular pipe in that series which is to be sounded. In the automatic 20 playing, *i. e.*, under the control of a perforated record sheet, two openings in the record sheet will always be brought simultaneously into register with two openings in the tracker board for each sound to be produced, one to operate a pneumatic 10 and so to select the series of pipes represented by the register chambers, and the other to operate a pneumatic 4 and so to select the individual pipe in such series. Of course 25 several pipes communicating with a single register chamber R may be simultaneously sounded, as may corresponding pipes in several register chambers.

Means will now be described for recording 30 the sounded notes on a sheet 17 which is continuously fed across a bar 18, against the rounded under surface of which it is stretched. The air channels S communicate by means of pipes 19¹, 19², etc. with pneumatics 20¹, 20², etc. and the pneumatics 10 communicate by means of pipes 21¹, 21², etc. with pneumatics 22¹, 22², etc. The series of pneumatics 20 and 22 may be arranged in separate rows, instead 35 of alternating with each other under the box 23, as shown in the drawing. To each of the pneumatics 20, 22 there is connected a style 24 having vertical movement in a hole 24¹ in a board 24² positioned below 40 the bar 18, so that when either of the said pneumatics is operated the respective style 24 is thrust against the sheet 17, and makes a mark or impression thereon.

At the sounding of each of the pipes 1, 45 one of the pneumatics 20 and one of the pneumatics 22 are operated so that each note produces two marks or impression on the sheet 17. If two or more pipes 1, communicating with a single register chamber 50 R, are simultaneously sounded, an equal number of pneumatics 20 and one pneumatic 22 are collapsed. By this means, a record is obtained of each pipe sounded, with a record of the register to which it 55 belongs.

For reproducing the music, the sheet 17, marked as described, is perforated where marked, and then fed as at 25, across the tracker board 6, as previously explained.

During the travel of the sheet 25 over the 70 tracker board the perforations in the sheet open the pipes 7^a and 26 to atmosphere, so that pneumatics 4 and 10 are operated in the same order in which they operated during the manual playing by which the notes 75 were recorded on sheet 17.

In regard to the actuation of the pneumatics 22, the construction may be modified by connecting said pneumatics to the pipes 16 or chambers 14^b, instead of making direct 80 connection to the pneumatics 10.

What I claim as my invention and desire to secure by Letters Patent of the United States is:

1. In an organ or like wind instrument 85 the combination, with a plurality of sounding elements grouped to make longitudinal and transverse series, of register chambers severally serving said transverse series of sounding elements, valves severally controlling the communication between the individual sounding elements and their respective register chambers, pneumatic motors for said valves, air channels severally serving the longitudinal series of the said pneumatic motors, a traveling sheet supporting means, movable styles positioned to mark a sheet traveling on said supporting means, pneumatic motors severally connected to 90 said styles, conduits severally connecting the register chambers to an equal number of said style-actuating pneumatic motors, and conduits connecting said air channels to the other style-actuating pneumatic motors, for the purpose set forth.

2. In an organ or like wind instrument 100 the combination, with a plurality of sounding elements grouped to make longitudinal and transverse series, of register chambers severally serving said transverse series of sounding elements, valves severally controlling the communication between the individual sounding elements and their respective register chambers, pneumatic motors for said valves, air channels severally serving 105 the longitudinal series of the said pneumatic motors, a traveling sheet supporting means, movable styles positioned to mark a sheet traveling on said supporting means, pneumatic motors severally connected to said styles, conduits severally connecting the register chambers to an equal number of said style-actuating pneumatic motors, and conduits connecting said air channels to the other style-actuating pneumatic motors, for the purpose set forth.

3. In an organ or like wind instrument 110 the combination, with a plurality of sounding elements, valves severally controlling the communication between the individual sounding elements and their respective register chambers, pneumatic motors for said valves, air channels severally serving the longitudinal series of the said pneumatic motors, a traveling sheet supporting means, movable styles positioned to mark a sheet traveling on said supporting means, pneumatic motors severally connected to 115 said styles, conduits severally connecting the register chambers to an equal number of said style-actuating pneumatic motors, and conduits connecting said air channels to the other style-actuating pneumatic motors, for the purpose set forth.

4. In an organ or like wind instrument 120 the combination, with a plurality of sounding elements, valves severally controlling the communication between the individual sounding elements and their respective register chambers, pneumatic motors for said valves, air channels severally serving the longitudinal series of the said pneumatic motors, a traveling sheet supporting means, movable styles positioned to mark a sheet traveling on said supporting means, pneumatic motors severally connected to 125 said styles, conduits severally connecting the register chambers to an equal number of said style-actuating pneumatic motors, and conduits connecting said air channels to the other style-actuating pneumatic motors, for the purpose set forth.

5. In an organ or like wind instrument 130 the combination, with a plurality of sounding elements, valves severally controlling the communication between the individual sounding elements and their respective register chambers, pneumatic motors for said valves, air channels severally serving the longitudinal series of the said pneumatic motors, a traveling sheet supporting means, movable styles positioned to mark a sheet traveling on said supporting means, pneumatic motors severally connected to said styles, conduits severally connecting the register chambers to an equal number of said style-actuating pneumatic motors, and conduits connecting said air channels to the other style-actuating pneumatic motors, for the purpose set forth.

tuating the valves in the two last-named series, a tracker board, manually controlled valves, and air conduits enabling the last-named pneumatic actuating devices to be served with air alternatively from the tracker board and from the manually controlled valves.

In witness whereof I have signed this specification in the presence of two witnesses.

ADALBERT ZOLLINGER.
